HIGH FIDELITY RECEIVER

Loren R. Kirkwood, Oaklyn, N. J., assignor to
 Radio Corporation of America, a corporation of
 Delaware

Application August 31, 1938, Serial No. 227,791

17 Claims. (Cl. 250—20)

The present invention relates to radio receiving systems, and has for its primary object, to provide means for tuning a radio receiving system through a predetermined frequency range with substantially uniform selectivity, whereby the fidelity in signal reception may be made more uniform throughout the tuning range, and otherwise enhanced.

In modern receivers, this involves the tuning of two or more signal receiving or radio frequency circuits through the same frequency range, and for a required high fidelity signal reproduction throughout the tuning range, it is necessary to include therein an R.-F. tuning system that shall provide substantially a constant band width.

It is, therefore, a further object of the present invention, to provide improved means for tuning two or more radio frequency or signal receiving circuits whereby the overall tuning response characteristic or band width thereof may be substantially constant throughout a relatively wide tuning range.

In radio receiving systems heretofore employed, it has been considered necessary to further increase the selectivity of the radio frequency or tunable signal circuits at the low frequency end of the tuning range, and to further broaden the selectivity at the high frequency end of the tuning range. In such systems, furthermore, all tuning inductances are made substantially identical for the same tuning range and as the secondaries of interstage coupling transformers, are coupled with primaries of low inductance for high frequency response that resonate above the tuning range.

Such tuning systems provide a variable band width in the tuning response characteristic which is relatively narrow at the low frequency end of the tuning range and relatively broad at the high frequency end, and compensation is required to reduce the high frequency gain accentuated by the use of low inductance primaries.

It is, therefore, also a further object of the present invention to provide an improved and simplified radio frequency tuning means involving two or more tunable circuits in a radio receiving system, that shall operate to broaden the tuning or reduce the selectivity at the low frequency end of the tuning range in conformity with the selectivity and broadness of the tuning determined for the high frequency end of the tuning range, thereby to maintain substantially constant band width in the frequency response

characteristic throughout the tuning range of the receiving system.

In a receiving system for which the present invention is particularly adapted, the two cascaded tunable circuits may comprise an antenna or R.-F. input circuit connected with a first R.-F. amplifier, and a second R.-F. circuit coupled to the output circuit of the first R.-F. amplifier and connected with the first detector. As is well known, the selectivity of such circuits increases as the frequency to which they are tuned is reduced. Each tunable circuit may include the secondary inductance of an R.-F. transformer and may be provided with a variable shunt tuning capacitor section, the various sections being controllable in unison with a section for tuning the oscillator.

It is also a still further object of the present invention to provide means for mistuning the signal receiving circuits by gradual change in alignment at the low frequency end of the tuning range and for restoring the alignment of said circuits at the high frequency end thereof, thereby to improve the band width response throughout the tuning range, and to cause the overall sensitivity to become more constant throughout the tuning range.

It is also an object of the present invention to provide means for preventing interference from undesired signals in the tuning system adapted for substantially uniform selectivity over a relatively wide frequency range, and an improved circuit arrangement therefor.

In carrying out the above and other objects of the present invention, and differing from present practice, the radio frequency and detector tuned circuits include unequal inductances, preferably provided by the secondary windings of suitable R.-F. coupling transformers, the primary inductances of which are equal and relatively high to resonate below the tuning range of the secondaries. The unequal tuning inductances are tuned by a gang or uni-control variable capacitor having sections of substantially equal capacity and variable capacity range, together with a suitable shunt trimmer capacitor for each section.

In general, the circuit arrangement for providing substantially uniform selectivity includes a plurality of tunable signal circuits in cascade relation to each other, each circuit including inductive and capacitive reactance elements. Means are provided for varying all of the capacitive reactance elements or all of the inductive reactance elements conjointly as by uni-control means, the

5 inductive reactance elements being of unequal inductance value when the capacitive reactance elements are made variable, and the capacitive elements being of unequal capacity value when
 10 the inductive reactance elements are made variable, in such a manner that the successive circuits are tunable to substantially the same frequency at the high frequency end of the tuning range, such as at 1500 kc., and are gradually
 15 mistuned to a greater degree increasingly as the tuning approaches the low frequency end of the tuning range such as 600 kc., for example, the tuning being such that the selectivity remains substantially uniform over the entire tuning range.

It has been found that in case the inductive reactance elements are provided by the secondaries of tunable radio frequency transformers, the desired mistuning may be obtained also by
 20 providing one primary in association with one of the secondaries with sufficient inductance to resonate at or below the tuning range desired, while the primary winding associated with another of the secondary windings is tuned to resonate at or above the desired tuning range.

25 The invention will, however, be better understood from the following description when considered in connection with the accompanying drawings illustrating a specific embodiment of the invention in the superheterodyne receiving system, and its scope will be pointed out in the appended claims.

In the drawings,

30 Figure 1 is a schematic circuit diagram of a portion of a radio receiving system of the superheterodyne type including the tunable R.-F. circuits in connection with the R.-F. amplifier and first detector, as a present preferred embodiment of the invention; and

35 Figures 2 to 5, inclusive, are curves showing frequency response characteristics illustrating the operation of the circuits of Fig. 1.

40 Referring to Fig. 1, 5 is the R.-F. amplifier tube and 6 is the first detector tube of a superheterodyne receiver of the type arranged for multiple wave band tuning. Only the A or broadcast band circuits are shown, for the sake of simplifying the drawings. Certain of the waveband-change switch-sections are indicated at 7, 8 and 9, since they are included in the grid circuits of the tubes 5 and 6 and the A band tuning circuits.

45 The signal input grid 10 of the R.-F. amplifier tube 5 is connected through a suitable grid resistor 11 with a bias potential supply lead 12, and through a coupling capacitor 13 to a switch contact 14 of the section 7, from which circuit connection is made through a movable connecting link 15 and a contact 16 with the high potential end of the A band tuning inductance 17. This inductance is provided by the secondary of a tunable input transformer and receives signal input energy from a high inductance primary winding 18 connected with an antenna or signal source 19.

50 The winding 18 resonates at a frequency below the broadcast band, while the secondary 17 is tunable through the broadcast band by a shunt variable tuning capacitor 20. The latter is one section of a variable tuning capacitor having additional sections 21 and 22 for tuning the first detector and oscillator respectively.

55 The tuning capacitor is of the grounded rotor type as indicated, and is arranged for unicontrol of the various sections as indicated by the dotted

connecting line 23. Each capacitor section is provided with a shunt trimmer capacitor indicated at 24. The capacitor section 20 and the shunt trimmer capacitor therefor are connected through a lead 25 with the input circuit of the tube 5 as indicated at 26. Since the secondary 17 is grounded as indicated at 27, this connection places the tuning capacitor 20 in shunt with the secondary 17.

60 In a similar manner, the signal input grid 28 of the detector or mixer output 6 is connected through a grid resistor 29 with the lead 12 and also is connected through a coupling capacitor 30 with a contact 31 of the switch section 9 from which the input circuit is completed through a movable connector 32 in the switch, a second contact 33 and a lead 34 to the high potential end of the "A" band tuning inductance 35 for the detector. This is also connected to ground at its low potential side, as indicated at 36.

65 The variable tuning capacitor section 21 and the trimmer capacitor therefore are connected in shunt with the inductance 35 through a lead 37 at a point indicated at 38. The inductance 35 is also provided with a fixed shunt capacitor 40.

70 The inductance 35 is the secondary of an inter-stage R.-F. coupling transformer, the primary 41 of which is connected in the plate circuit 42 of the first F.-F. amplifier tube 5. The inductance of the primary is relatively high so that it resonates at a frequency below the broadcast band to which the secondary 35 is jointly tunable along with the secondary 17.

75 As the oscillator circuit is not part of the present invention, the same is not shown except for the tuning capacitor 22 therefor and the grid input circuit 43 for the detector or mixer tube in connection with the oscillation input grid 44. Signals at the intermediate frequency are derived from the detector 6 through the output circuit 45 and applied to the usual R.-F. amplifier (not shown), through a coupling transformer indicated at 46. As the amplifier does not concern the present invention, the circuits thereof are also omitted from the drawings for the sake of simplifying the same.

80 The output plate circuit of the R.-F. amplifier 5 is coupled to a trap circuit 50 comprising a variable inductance 51 and a capacitor 52 in series, shunted by a resistor 53 and a capacitor 54. The trap circuit is grounded as indicated at 55 and the high potential end thereof is connected through a contact 56 on the switch section 9, a movable link 57 and a second contact 58 with a coupling capacitor 59 to the plate circuit. This places the trap circuit in shunt with the primary winding 41 since the plate supply lead indicated at 60 is by-passed to ground 61 through a by-pass capacitor 62.

85 The trap circuit is tunable to an interfering signal by means of a variable magnetite core indicated at 63. The use of the trap circuit in the primary circuit of the R.-F. amplifier tube has been found to be effective to reduce interference when utilizing band-pass tuning means providing uniform selectivity throughout the tuning range and is more effective for this purpose than if placed in the antenna circuit. As normally provided in the circuit the trap is tuned to the intermediate frequency to prevent interference from signals in the intermediate frequency range. The resistor 53 is used to damp the parallel resonance peak occurring above the series resonance peak, and does not broaden the 75

series resonance peak appreciably. With the arrangement shown, it will be seen that the trap circuit is interposed in the signal tuning system between the two variably tunable circuits, in shunt with the primary of the interstage R.-F. transformer.

As previously referred to, the coils or inductances 17 and 35, in the cascaded signal receiving circuits, increase in selectivity as the frequency is reduced. Therefore, to provide a constant band width, the circuits are mistuned at the low frequency end of the tuning range. For the broadcast band this may be in the neighborhood of 600 kc. This is done by increasing the inductance of one coil over the other, for example, by winding more turns on one coil than on the other. The difference between the resonance frequencies of the circuits contained in the coils 17 and 35 at substantially 600 kc. may be made approximately 10 kc. Since the amplification is normally higher at the low frequency end of the range due to the low frequency primary, the mistuning tends to cause the overall sensitivity to be more constant in tuning from the high frequency to the low frequency end of the range.

Referring to Fig. 2, if the inductances 17 and 35 are aligned to the same frequency, the overall response of the tuning system will be as shown by the curves 65, 66 and 67 corresponding to 600, 1,000 and 1500 kc., respectively. If the maximum modulation frequency which is desired is indicated by the frequency range a , it will be seen that considerable attenuation will be obtained, particularly at the low frequency end of the tuning range, resulting in the loss of fidelity.

However, if equal variable capacitors in each circuit such as the capacitors 20 and 21 are used, and if the same coils or inductances are used except that they are adjusted in inductance so that the resonance frequencies are 10 kc. apart and aligned at 1500 kc., it has been found that the width of the modulation frequency band a will be substantially constant throughout the tuning range, as is indicated in Fig. 3 in connection with the curves 68, 69 and 70 corresponding respectively to the tuning of the circuits at 600, 1,000 and 1,500 kc., respectively. It will be noted that the desired modulation band width a falls well within the three curves without appreciable attenuation throughout the tuning range.

The effect of mistuning may be more readily seen by referring to Fig. 4, wherein the tuning response of the circuit, the input circuit including coils 17, is indicated by the curve 71 and the tuning response of the circuit containing the coil 35 is indicated by the curve 72. However, either of the circuits may be tuned to the higher frequency. In the present example, one circuit is tuned to 595 kc. as indicated, and the other circuit is tuned to 605 kc., providing an overall response characteristic as a product of the two response characteristics and indicated by the overall curve 73.

Fig. 5 shows the overall R.-F. amplifier throughout the tuning range, the curve 75 being the response before mistuning, and the curve 76 indicating the response characteristic after mistuning.

The circuits are aligned at the high frequency end of the tuning range, such as at 1,500 kc., by means of the shunt trimmer capacitors 24. The capacitors 20 and 21 may be equal, that is, substantially identical in capacity and capacity range variation, thereby simplifying the construction of the receiver and lowering the cost.

While this represents a departure from previous practice and substantially a reversal of certain methods previously employed in connection with radio receiving systems for providing variations in selectivity with tuning, it has been found to provide a substantially constant band width in the tuning response of radio receiving systems adapted for high fidelity reproduction. It has the advantage that the variable tuning capacitors employed may be made alike and uni-controlled, while the circuit changes referred to include the relative values of the tuning inductances in the various successive cascaded circuits.

For the broadcast tuning range of the present example, the inductance in one circuit may be 4 percent greater than in the other at 600 kc. between the two cascaded tunable circuits, such as R.-F. and detector circuits of the usual superheterodyne receiving system to provide a difference in resonance at the low frequency end of the broadcast range of substantially 10 kc.

At the high frequency end of the tuning range, the two circuits referred to are aligned substantially to the same frequency by the trimmer capacitors and the divergence in resonance between the two cascaded circuits increases from the high frequency end of the tuning range toward the low frequency end thereof as the tuning of the receiving system is varied.

Mistuning of the circuits at the low frequency end of the tuning range compensates for the tendency for the selectivity to increase as the frequency to which the circuits are tuned is reduced. At the same time, since the amplification is normally higher at the low frequency end of the tuning range, the mistuning tends to provide a more constant gain or sensitivity for the receiving system. However, the low frequency or high inductance primary windings tend to increase the low frequency gain and prevent the mistuning from excessively reducing the gain at the low frequency end of the range.

While the invention has been described in connection with a radio tuning system having a multiple unit variable capacitor, as has hereinbefore been referred to, the tuning may be effected by variable inductance elements in connection with fixed capacitor elements, in which case the inductance elements 17 and 35 may have equal inductance values while the capacitors 20 and 21 may have differing capacity values to provide misalignment of the tuning at the low frequency end of the tuning range as the inductance elements are varied conjointly after the manner of the capacitors 20, 21 and 22, by common control means.

I claim as my invention:

1. The method of selectively receiving radio signals within a predetermined frequency range, which comprises effecting an initial selection of a signal frequency within said range, amplifying a received signal at the selected frequency, excluding undesired signals from the amplified signal, and conjointly selecting the amplified signal at a frequency which differs from the first named frequency by an increasing amount as signals of lower frequencies are selected within said frequency range.

2. The method of receiving radio signals which comprises tuning to select signals throughout a predetermined frequency range at the same resonance frequency in a plurality of cascaded circuits at the high frequency end of said range and at differing resonance frequencies in said circuits at the low frequency end of the range,

and causing the difference in said resonance frequencies to be reduced as the tuning approaches the high frequency end of the tuning range.

3. In a radio receiving system, means for tuning said system through a predetermined frequency range with substantially uniform selectivity, comprising two tunable signal circuits connected in cascaded relation to each other and comprising inductance and variable capacitor elements, said capacitor and inductance elements providing inductive and capacitor tuning reactances in said circuits, one of said reactances of like character in each circuit being conjointly variable through the same reactance connection 10 range and the other of said reactances in each circuit being of such differing fixed reactance value that said circuits are mis-tuned increasingly toward the low frequency end of the tuning range with respect to a desired signal frequency, 15 and means for causing said circuits to reach substantial alignment at a desired signal frequency at the high frequency end of the tuning range.

4. In a radio receiving system, means for tuning said system through a predetermined frequency range with substantially uniform selectivity, comprising two tunable signal circuits connected in cascaded relation to each other and comprising inductance and variable capacitor elements, said capacitor elements having substantially the same capacity variation range and said inductance elements having differing inductance values, whereby said circuits are mis-tuned increasingly toward the low frequency end of the tuning range with respect to a desired signal 25 frequency, and means for causing said circuits to reach substantial alignment at a desired signal frequency at the high frequency end of the tuning range.

5. In a radio receiving system comprising two tunable signal receiving circuits arranged in cascaded relation to each other, the combination of unequal inductance elements in said circuits and substantially equal tuning capacitors in shunt with said inductance elements, and the difference 40 in inductance between said inductance elements being such that a gradual departure between the resonance frequencies of said circuits is effected as the tuning approaches the low frequency end of the tuning range.

- 50 6. In a radio receiving system comprising two tunable signal receiving circuits arranged in cascaded relation to each other, the combination of unequal inductance elements in said circuits and substantially equal tuning capacitors in shunt with said inductance elements, a trimmer capacitor for each of said first-named capacities for aligning said circuits to the same resonance frequency at the high frequency end of the tuning range thereof, and the difference in inductance 55 between said inductance elements being such that a gradual departure between the resonance frequencies of said circuits is effected as the tuning approaches the low frequency end of the tuning range.

- 65 7. In a radio receiving system, the combination of means providing a tunable signal input circuit comprising an inductance element and a shunt variable tuning capacitor therefor, a coupling winding for said inductance element for applying signals to said input circuit resonant at a frequency of the order of the lower end of the tuning range of said circuit, a second signal input circuit comprising a second inductance element and a second shunt variable tuning capacitor therefor, means for conveying signals

from said first-named circuit to the second-named circuit including an amplifier having an output circuit, a winding in said output circuit coupled to the inductance element of said second-named circuit and resonating at a frequency 5 below the tuning range of said second-named circuit, means for conjointly moving said tuning capacitors to tune said circuits through the substantially same frequency range, the inductance element in one circuit having a percentage 10 greater inductance than that in the other circuit by an amount sufficient to cause said circuits to gradually depart from resonance to a desired signal increasingly toward the low frequency end of the tuning range. 15

8. In a tunable radio receiving system, the combination of a tunable signal input transformer and an interstage radio frequency transformer, said transformers having secondary windings of unequal inductance value, means for tuning said secondary windings through a predetermined frequency range comprising substantially equal capacity variable tuning capacitors, one connected in shunt with each of said secondary windings, means for conjointly controlling said tuning capacitors for tuning said windings simultaneously through the same frequency range, the inductance of one secondary winding being greater than that of the other by an amount sufficient to extend the band width of the 20 receiving system at the low frequency end of the tuning range to equal at least the band width of the tuning system at the high frequency end of the tuning range. 25

9. In a tunable radio receiving system, the combination of a tunable signal input transformer and an interstage radio frequency transformer, said transformers having secondary windings of unequal inductance value and primary windings resonant at a frequency below the tuning range of said system, means for tuning said secondary windings through a predetermined frequency range comprising substantially equal capacity variable tuning capacitors, one connected in shunt with each of said secondary 40 windings, means for conjointly controlling said tuning capacitors for tuning said windings simultaneously through the same frequency range, the inductance of one secondary winding being greater than that of the other by an amount sufficient to extend the band width of the receiving system at the low frequency end of the tuning range to equal at least the band width of the tuning system at the high frequency end of the tuning range, and means including a shunt 45 trimmer capacitor for each of said variable tuning capacitors for aligning the tuning of said circuits to the same frequency at the high frequency end of the tuning range. 50

10. In a radio signal conveying system, the combination of means for tuning said system through a predetermined frequency range including a pair of tunable signal circuits arranged in cascade relation to each other, and means in each of said circuits cooperating to provide substantially a constant band width in the frequency response of said system throughout the tuning range thereof, said last named means including an inductive reactance element and a capacitive reactance element in each of said circuits, like 65 reactance elements of one type in each of said circuits being substantially equal and conjointly variable, and the reactance elements of the opposite type being unequal and fixed to values for effecting resonance in the said circuits at sub- 70 75

stantially the same frequency adjacent the high frequency end of the tuning range and for effecting a gradual divergence in the resonance frequencies of said circuits as the tuning approaches the low frequency end of the tuning range, thereby to provide substantially uniform selectivity over the said tuning range.

11. In a radio signal conveying system, the combination of a tunable signal input transformer and an interstage signal conveying transformer, said transformers having secondary windings and primary windings associated therewith, one of said primary windings being resonant at a frequency of the order of the low frequency end of the tuning range of the secondary windings, a shunt tuning capacitor for each of said secondary windings, said tuning capacitors being of substantially equal capacity value and tuning variation range, and means for conjointly controlling said tuning capacitors for tuning said windings simultaneously through the same frequency range, the resonance frequencies of the primary windings being such that the over-all band width of the frequency response of the conjointly tunable circuits at the low frequency end of the tuning range is substantially equal to the over-all band width of the circuits at the high frequency end of the tuning range.

12. In a radio signal conveying system, the combination of means for tuning said system through a predetermined frequency range including a pair of tunable signal circuits arranged in cascade relation to each other, and means in each of said circuits cooperating to provide substantially a constant band width in the frequency response of said system throughout the tuning range thereof, said last named means including unequal inductance elements in said circuits for causing divergence in the resonance frequencies of said circuits at the low frequency end of the tuning range, and means for causing the resonance frequencies of said circuits at the high frequency end of the tuning range to be substantially equal.

13. In a superheterodyne receiving system, the combination with a radio frequency amplifier and a first detector, of tunable signal input circuits for said amplifier and detector, an inductance element in each of said circuits, and a variable tuning capacitor in shunt therewith, said inductance elements being of unequal inductance value, and said tuning capacitors being of substantially equal capacity value and capacity variation range conjointly operable in unison.

14. In a superheterodyne receiving system, the combination with a radio frequency amplifier and a first detector, of tunable signal input circuits for said amplifier and detector, an inductance element in each of said circuits, a variable tuning capacitor in shunt therewith, said inductance

elements being of unequal inductance value, and said tuning capacitors being of substantially equal capacity value and capacity variation range conjointly operable in unison, an output circuit for said amplifier, and a tunable wave trap in said circuit.

15. In a superheterodyne receiving system, the combination with a radio frequency amplifier and a first detector, of tunable signal input circuits for said amplifier and detector, an inductance element in each of said circuits and a variable tuning capacitor in shunt therewith, said inductance elements being of unequal inductance value, and said tuning capacitors being of substantially equal capacity value and capacity variation range, an output circuit for the said amplifier including a primary winding resonant at a frequency below the tuning range of said system and coupled to the inductance element of said detector circuit, and an adjustable wave trap circuit connected in shunt with said primary winding.

16. In a superheterodyne receiving system, the combination with a radio frequency amplifier and a first detector, of tunable signal input circuits for said amplifier and detector, an inductance element in each of said circuits and a variable tuning capacitor in shunt therewith, said inductance elements being of unequal inductance value, and said tuning capacitors being of equal capacity value and capacity variation range, an output circuit for the said amplifier including a primary winding resonant at a frequency below the tuning range of said system and coupled to the inductance element of said detector circuit, and an adjustable wave trap circuit connected in shunt with said primary winding, said wave trap circuit including an inductance having a movable magnetite core and a tuning capacitor in series therewith, a shunt resistor for limiting the impedance of said series connected inductance and capacitor, and means for connecting said wave trap in circuit with said amplifier.

17. In a superheterodyne receiver, a radio frequency and a detector circuit, means for conjointly tuning said circuits throughout the same frequency range, comprising an inductance element in each circuit and a shunt variable tuning capacitor therefor, means for aligning said circuits to the same frequency adjacent the high frequency end of the tuning range of said circuits and the inductance elements in said circuits having inductance values differing by a predetermined percentage one with respect to the other to provide a predetermined departure from resonance for said circuits, one with respect to the other, at the low frequency end of the tuning range.

LOREN R. KIRKWOOD. 60
